UNITED STATES PATENT OFFICE

SCHUYLER C. HULETT, OF SPOKANE, WASHINGTON

CLOTHES HANGER

Application filed June 15, 1931. Serial No. 544,433.

My present invention relates to an improved clothes hanger or suit hanger for use in supporting both men's suits and clothes as well as women's dresses, suits and other garments. While the improved clothes hanger is designed especially for use by clothes cleaning establishments, laundries, dyers, clothes pressers, and other commercial operators, it is also useful as a household article.

As is well known, after a suit or garment has been laundered, cleaned and pressed, usually in a steam press, and while moist, the suit or garment is placed upon a wire clothes hanger or garment support, for delivery.

15 In many instances, when the garment dries on a wire hanger or support, the wire, due to the weight of the garment supported thereon, forms an acute and undesirable crease in the goods or material of the garment.

The purpose of my invention is to provide the usual wire hanger or support with tubular casings or covers that will insure a much larger surface area for the support and thereby reduce the acuteness or wholly eliminate the formation of a crease in the moist garment as it dries on the hanger.

In carrying out my invention the wire hanger, which in itself is comparatively inexpensive, is equipped with inexpensive casings or covers for the cross bar and converging side arms and means are provided whereby the covers may be placed in position with facility, with a minimum of labor, and 35 in a minimum period of time.

The tubular casings or covers are preferably formed of cardboard, straw board or heavy paper, and constructed in such manner that they can readily be placed upon the cross bar and arms of the hanger. The invention consists in certain novel combinations and arrangements of parts as will hereinafter be more fully set forth and claimed.

In the accompanying drawing I have illustrated one complete example of the physical embodiment of my invention wherein the parts are combined and arranged according to the best mode I have thus far devised for the practical application of the principles of my invention.

Figure 1 is a view showing a wire hanger equipped with the casings of my invention.

Figure 2 is a fragmentary view showing the manner of "screwing" a casing on the cross bar of the hanger.

The suit or clothes hanger is of the usual type for use in supporting men's suits, coats, trousers &c. and women's dresses, suits, coats, &c., and is provided with the cross bar 1, converging side arms 2, 2, and bends 3. The arms are fastened together by twisting at 4, and the hook 5 is utilized to suspend or support the hanger in usual manner.

The cross bar and side arms are provided with tubular casings 6, 7, and 8, and as shown these tubes, which may be fashioned from strips of cardboard, straw board or other suitable material, are provided with a spiral slit or slot 9. The tubes are formed, as on a mandrel, while the material is in a plastic condition, by wrapping a single layer or strip in spiral formation on the mandrel, and when dried, the tube is of cylindrical shape, and the material of the tube possesses sufficient resiliency or elasticity to permit placing the tube on the wire of the hanger without materially deforming the shape of the tube or casing.

Thus, at one end of the tube, the spiral slit, or the end of the slit, may be slipped over the wire, then, as indicated by the arrows in Figure 2, the tube is "screwed" on the wire bar 1 until the tube, which has previously been cut to the proper length, covers substantially the length of the bar. The tubes 7 and 8 are "screwed" on the arms 2, 2, in a similar manner, and after the tubes have been properly located they present the appearance as shown in Figure 1.

At the forward and rear ends of the tubes, notches 10, 10 may be cut in the wall of the cylindrical tube, especially tube 6, and these notches, which engage the wire at the bends 3, 3, prevent the tube from rotating or turning on the wire bar as 1. Thus, when a pair of trousers are folded and suspended over the tube 6, even though one fold may be heavier than the other and thus have a tendency to turn the tube, the latter is prevented from turning. It will be apparent also that the friction between the cloth or material of the

trousers and the exterior surface of the straw-board tube, will prevent the trousers from slipping off of the non-rotatable tube. As is well known, the friction between the material of the trousers and the wire cross bar, is frequently insufficient to hold the trousers from slipping, but when the tube 6 is used this possibility of displacement of the trousers is eliminated.

10 Ordinarily the bends 2 between the cross bar and the arms are sufficient to prevent turning of the tubes 7 and 8, but these tubes also may have the notches 10 applied thereto to engage the wire and prevent turning of the tubes 7 and 8.

15 Having thus fully described my invention, what I claim as new and desire to secure by Letters Patent is:—

20 The combination with a wire clothes hanger, of a tube of resilient material and cylindrical in shape, said tube having a spiral slit throughout its length to permit "screwing" on the wire, and notches in the ends of the tube for co-action with the wire to prevent turning of the tube on the wire.

25 In testimony whereof I affix my signature.
SCHUYLER C. HULETT.
